UNITED STATES PATENT OFFICE.

HARMAN F. ACKERMAN, OF CLEVELAND, OHIO.

DESIGN FOR A PAPER-WEIGHT.

SPECIFICATION forming part of Design No. 25,911, dated August 11, 1896.

Application filed June 2, 1896. Serial No. 594,060. Term of patent 3½ years.

To all whom it may concern:

Be it known that I, HARMAN F. ACKERMAN, a citizen of the United States, residing at Cleveland, in the county of Cuyahoga and State of Ohio, have invented and produced a new and original Design for Paper-Weights, of which the following is a specification, reference being had to the accompanying drawing, forming a part thereof.

10 The figure is a perspective view of a paper-weight of my design.

The leading features of my design consist of a pedestal A, which is circular in horizontal section at all points. This pedestal includes a shaft a , a base a' , larger than the shaft, and a capital a^2 , of several diameters progressively smaller than the shaft. Upon

the pedestal is the figure of a man dressed in the costume in vogue a hundred years ago. He is standing erect, holding in his right hand 20 a staff which rests upon the pedestal, and in his left hand he carries a cocked hat resting upon his forearm, which is held in a substantially horizontal position.

I claim—

25 The design for a paper-weight substantially as herein shown and described.

In testimony whereof I affix my signature in presence of two witnesses.

HARMAN F. ACKERMAN.

Witnesses:

E. L. THURSTON,
H. M. HUTCHISON.
